METHOD OF AND APPARATUS FOR HOLDING
AND RELEASING BOWLING BALLS

Henry K. Hess, Syracuse, N. Y.

Application February 2, 1935, Serial No. 4,619

9 Claims. (Cl. 273—37)

This invention relates to a method of and apparatus for holding and releasing bowling-balls in the act of projecting the ball along the runway of a bowling alley, the balls being provided with suitable finger-holes or openings extending inwardly from the periphery toward the center thereof in circumferentially spaced relation for receiving the thumb and one of the remaining fingers of the player's hand so that the intervening portion of the ball may be gripped between the thumb and finger with sufficient pressure to overcome not only the weight of the ball but also the centrifugal force of its swinging movement necessary to project and to properly direct the ball along the runway.

It is common practice to use the larger and therefore heavier balls by reason of their greater scoring efficiency but it frequently happens that the lighter weight players and particularly the women players do not have sufficient finger strength to properly hold and propel these balls along the runway and that even the stronger experienced players find that the strain upon the fingers and hand is too severe to continue the practice for long periods of time without frequent intervals of rest.

The main objects of the present invention are:—1st, to provide a simple and highly efficient means for holding the ball in the hand with considerably less finger pressure than has heretofore been required; 2nd, to enable the ball to be more easily and accurately directed along the runway so that the score may be more dependent upon the skill of the player; and 3rd, that the ball may be released from the hand by simply releasing the fingers in a manner quite similar to that heretofore commonly practiced.

Another object is to suspend the ball-gripping device from an overhead transverse track so that it may be brought into alignment with any one of a plurality of parallel runways ready for use with the same or a different ball.

A further object is to provide the suspensor with an elastic section capable of partially supporting the weight of the ball when the latter is held by the gripping device and also adapted to yield under such weight and swinging motion of the arm for relieving the player from excessive muscular strains without in any way interfering with the free projection and release of the ball along the runway.

Other objects and uses relating to different parts of the apparatus will be brought out in the following description:

In the drawings:—

Figure 1 is a perspective view of my invention showing the manner of using the same by a person in a sitting position and also showing portions of a runway and overhead track.

Figure 2 is an enlarged perspective view of the detached ball-gripping device in its extended or released position with the hand-loop thereon, the hand being indicated by dotted lines in position to allow the gripping-strap to extend under its own resiliency.

Figure 3 is an enlarged sectional view of a portion of the ball with finger-receiving bushings in the holes therein and the gripping device operatively engaged in said bushings preparatory to throwing the ball along a runway taken on line 3—3 of Figure 2.

Figure 4 is a detail sectional view of the gripping device taken on line 4—4, Figure 2.

Figure 5 is a perspective view of one of the bushings.

Figure 6 is an enlarged longitudinal sectional view of the bushing taken on line 6—6, Figure 5.

Figure 7 is a transverse sectional view of the same bushing taken on line 7—7, Figure 6.

As illustrated, this apparatus is adapted to be used for supporting a bowling-ball A having inwardly convergent radial openings a arranged in circumferentially spaced relation for receiving the thumb and one of the remaining fingers of the player's hand B and comprises a pair of cylindrical bushings 1, a gripping device 2, a suspensor 3 for the gripping device, and an overhead track or guide rail 4 along and upon which the suspensor 3 is adapted to be moved and oscillated in a manner and for a purpose hereinafter described. (See Figure 1.)

The bushings 1 are inserted axially into their respective openings a with their outer ends substantially flush with the periphery of the ball for receiving the thumb and finger of the player and are preferably divided longitudinally through one side at 5 and tensioned to automatically expand against the walls of their openings to assist in holding them in operative position but may be cemented or otherwise firmly secured to said walls to prevent accidental displacement thereof so that the divisions may extend along the centers of the distal sides of said openings as shown in Figure 3.

The proximal sides of the bushings 1 are provided with inner recesses 6 in opposed relation to their respective divisions 5 for receiving cylindrical segments 7 of soft rubber or equivalent

material having their inner faces corrugated longitudinally for frictional engagement with the fingers or with a finger-operated gripping strap hereinafter described, each recess being defined 5 by a pair of circumferentially spaced lengthwise ribs 8 and an outer end rib 9 to assist in holding the segment 7 in operative position.

The inner ends of the recesses 6 may be left open to facilitate the endwise insertion and removal of their segments 7 but obviously, these 10 segments may be otherwise seated in their respective recesses and firmly held therein by cement or other agency, the main object being to provide a maximum friction grip for holding the ball 15 against its own weight and centrifugal force with a minimum finger pressure and thereby to reduce the muscular strain upon the player in the act of projecting the ball along the runway.

20

Gripping device

The gripping device comprises a flexible and more or less resilient strap 10 of leather, soft rubber or equivalent material of somewhat greater length than the distance between the centers of 25 the finger holes *a* in the ball A and preferably of slightly less width than the diameter of said holes so that its ends may be easily deflected in one direction from their normal positions under pressure of the thumb and finger and inserted 30 into the finger holes of the bushings 1 and then firmly pressed by the same members into engagement with the inner surfaces of the segments 7.

The inner sides of said ends are also corrugated longitudinally at 10' to co-operate with the corrugated surfaces as 7' of the segments to further assure a firm grip upon the ball with a minimum pressure when throwing the ball and also to assure a quick and positive release of the ball when the pressure of the fingers is relaxed, it being understood that during the operation of compressing the ends of the strap into the finger holes in the ball and against the corrugated sides of the bushings 1, the thumb and finger actually enter the holes so that the finger action in holding and releasing the ball is quite similar to the usual practice.

Suitable means is provided for holding the intermediate portion of the grip 10 in the hand of the player in such manner that its ends may 50 be conveniently compressed toward each other and inserted into the finger holes in the ball by the thumb and finger for gripping and releasing the ball, said means consisting, in this instance, of a relatively small but light and strong clamping frame 11 and a supporting loop 12 therefor adapted to be passed around the player's hand.

The clamping frame 11 may be made of aluminum or other suitable material and is provided with relatively shallow rectangular slots or openings 13 and 14 in different planes at right angles to each other and separated by an intervening partition 15 for receiving the straps 10 and 12 respectively in a manner presently described.

The bottom portion 16 of the frame is elongated in the direction of extension of the adjacent portion of the hand-loop 12 and has its lower face 16' concaved in said direction to conform more or less closely to the peripheral contour of the ball A to rest thereon when compressing the ends of the gripping strap 10 into engagement with the corrugated faces of the segments 7.

The upper wall of the slot 13 and lower wall of the slot 14 are provided with central threaded apertures for receiving clamping screws 17 and 75 18 by which the straps 10 and 12 are firmly locked

to the frame 11 against accidental displacement therefrom, the front end of said frame being provided with an upwardly projecting flange 19 terminating in an eye 20 for attachment to the lower end of the suspensor 3 in a manner herein- 5 after described. (See Figures 2 and 4.)

The gripping strap 10 is passed endwise through the opening 13 to extend equal distances beyond opposite ends of the frame 11 sufficient to enter the major portions of the lengths of their respective bushings 1 when the bottom of the frame is resting on the periphery of the ball between the openings *a* as shown in Figures 3 and 4.

The hand loop 12 preferably consists of a leather or equivalent flexible strap which is 15 passed endwise through the opening 14 in the frame 11 and is of sufficient length to pass entirely around the main body of the hand between the thumb and forefinger, one end of the strap being provided with a buckle 21 for receiving 20 the other end and thereby permitting adjustment of the strap to conform to hands of different sizes.

The portion of buckle-end of the strap 12 adjacent the buckle 21 is provided with an opening 22 through which the eye 20 is adapted to project when the loop 12 is fastened around the hand thus permitting the eye to be readily attached to or detached from the suspensor 4 as may be desired.

The suspensor 3 comprises a cord or cable 23 and a coil spring 24 attached to each other end to end in any suitable manner to form an extensible and contractible connection between the ball A and overhead track 4 for partially supporting the weight of the ball and permitting the latter to be oscillated forwardly and backwardly preparatory to throwing the same along the runway of the bowling alley.

The lower and upper ends of the cord or cable 23 are provided with swiveled snap-hooks 25 and 25' engaging respectively in the eye 20 of the ball-gripping device 2 and an eye 26 on the lower end of the coil spring 24 which is also provided at its upper end with a snap-hook 27 engaging in a ring 28 on the track 4, the latter being supported from 45 the ceiling of the bowling alley through the medium of eye-bolts 29 as shown in Figure 1.

The coil spring is tensioned to substantially balance the weight of the ball when the latter is held by the gripping device through pressure of the ends of the strap 10 against the inner faces of the segments 7 of the bushings 1 in the finger holes *a* in the manner described and as shown more clearly in Figure 3.

The cable 23 may be also adjusted vertically in the snap-hook 25 to vary the height of the ball to suit the convenience of the player and when properly adjusted may be knotted to hold it in its adjusted position.

Operation

The gripping strap 10 may be used without the supporting frame 11 and suspensor 24, under which conditions it would be grasped in the hand 65 with the thumb and finger engaged with its opposite ends for compressing said ends toward each other and inserting the latter into the finger-openings in the bushings 1 followed by further compression thereof against the inner faces of the segments 7 with sufficient pressure to hold the ball in the act of throwing said ball along the runway as C, it being understood that the relaxation of such pressure will instantly release 75 the ball from the gripping strap and allow the 75

latter to remain in the hand of the player ready for re-use.

When the frame 11 with the gripping strap 10 and hand-loop 12 thereon are used, the frame 11 is placed in the palm of the hand which is passed through the loop 12 to support the gripping device in the hand with the thumb and finger engaged with the opposite ends of the strap 10 whereupon the ends of the strap will be compressed toward each other and inserted into their respective finger openings in the ball until limited by the engagement of the lower side of the frame 11 with the periphery of the ball between said holes followed by the pressure of the ends of the strap against the inner faces of the segments 7 sufficient to hold the weight of the ball which may then be swung by hand and released at will by simply relaxing the pressure.

If it is desired to use the suspensor 3, the lower end thereof may be easily and quickly attached to the eye 20 of the frame 11 and the ends of the gripping strap 10 compressed by the fingers into engagement with the segments 7 in the manner described, thus permitting the weight of the ball to be yieldingly and partially supported by the suspensor 3 and rail 4 and also permitting the ball to be swung in any direction to propel the same along the runway.

Under these latter conditions, the gripping device and its suspensor may be moved along the track 4 to register the same with different parallel runways for use by the same player with the same ball or different balls or by different players upon any one of the runways.

The apparatus shown is particularly simple and efficient in relieving the player from excessive irritation of the fingers and also from overstrain of the muscles and aids materially in more accurately directing the ball along the runway to any desired pin or pins for producing a maximum score or count.

It is evident, however, that various changes may be made in the detail construction without departing from the spirit of the invention.

I claim:

1. In an apparatus for holding and releasing a bowling-ball in the act of throwing the ball along an alley, a hand-grip having flexible ends adapted to be inserted with and by the fingers into the finger openings in the ball and pressed by the same fingers against the walls of said openings to temporarily hold the ball under the finger pressure and to automatically release the ball from the hand-grip when the pressure is relaxed.

2. An apparatus for holding and releasing a bowling-ball in the act of throwing the ball along a runway, the ball being provided with holes for receiving certain fingers of the player's hand, said apparatus comprising a flexible strap having its ends adapted to be engaged by said fingers to move therewith into and out of their respective holes and into and out of holding engagement with the walls thereof at the will of the player.

3. The herein described method of holding and

releasing a bowling ball having holes for certain of the fingers of the player's hand, said method consisting in placing the ends of a flexible strap in said holes, holding said ends in engagement with the walls of the holes by the fingers in the holes with sufficient pressure to support the weight of the ball preparatory to throwing the same, releasing the finger pressure on the ends of the strap to release the ball, and retaining the strap in the hand when the ball is released. 10

4. An apparatus for holding and releasing a bowling-ball in the act of throwing the ball along a runway, the ball being provided with holes for receiving certain fingers of the player's hand, said apparatus comprising a flexible strap having 15 its ends adapted to be engaged by said fingers to move therewith into and out of their respective holes and into and out of holding engagement with the walls thereof at the will of the player, and a relatively rigid clamping member engaging 20 the intermediate portion of the strap and adapted to engage the periphery of the ball between said holes to enable said ends to enter proper distances within the holes.

5. An apparatus for holding and releasing a 25 bowling-ball in the act of throwing the ball along a runway, comprising a gripping device operable at will for engaging and disengaging the ball, and an oscillating suspensor for said gripping device adapted to be oscillated through the forward and backward movement of the gripping device with the ball thereon. 30

6. The herein described method of manipulating a bowling-ball in the act of throwing the same along a runway, consisting in supporting 35 the ball in a gripping device releasable at will, attaching said device to an oscillating suspensor, oscillating the suspensor with the ball thereon, and releasing the gripping device to release the ball during a forward swinging movement of said 40 suspensor.

7. An apparatus as in claim 5 in which the suspensor is provided with an elastic section tensioned to balance at least a part of the weight of the ball. 45

8. An apparatus for holding and releasing a 50 bowling-ball in the act of throwing the ball along a runway, comprising a gripping device adapted to engage in the finger holes of the ball by pressure of the fingers in said holes, and a loop attached to said device and adapted to be passed around the hand of the player to support the same when the ball is released, said device being releasable at will. 55

9. An apparatus for holding and releasing a 55 bowling-ball in the act of throwing the ball along a runway, comprising a gripping device operable at will for engaging and disengaging the ball, an overhead track extending transversely of the runway, and an oscillating suspensor for the gripping device movable along said track and adapted to be oscillated through the forward and backward movement of the gripping device. 60
